UNITED STATES PATENT OFFICE.

HENRY H. BROWNE, OF MOUNT VERNON, NEW YORK.

IMPROVEMENT IN ADVERTISING DEVICES.

Specification forming part of Letters Patent No. 78,923, dated June 16, 1868.

To all whom it may concern:

Be it known that I, HENRY H. BROWNE, of Mount Vernon, in the county of Westchester, in the State of New York, have invented a new and useful Improvement in Pocket-Mirror Business-Cards; and I do hereby declare that the following is a full, clear, and exact description thereof, which will enable those skilled in the to make and use the same, reference being had to the accompanying drawings, forming part of this specification, in which drawings—

Figure 1 represents that side of the card on which is placed the mirror. Fig. 2 represents the obverse side, on which is placed a business designation or other information. Fig. 3 is a cross-section of the card.

Similar letters indicate corresponding parts. This invention consists in the combination of a business or advertising card with a mirror, the former being placed on or at the back of the mirror, and being either in one piece rimmed over the edge of the mirror or connected therewith (if separate from the back of the mirror) by a metallic or other suitable rim, substantially as herein described. I combine therewith also a pin-cushion.

The letter *a*, Fig. 1, designates a mirror, which may be of glass or other material; and the letter *b* designates a business or advertising card formed on or at the back of the mirror, the two being connected or held together by means of a rim, *c*, turned down over the edges of the combined card and mirror, so as to hold them together when they are made of independent pieces set back to back, as in Figs. 1, 2, and 3.

The surface *b*, which contains the business designation or other information, is made of paper, card-board, metal, wood, or other material, and the designation or other informa-

tion placed on it may be put thereon by printing, engraving, or stamping, according to the nature of the material or other circumstances.

The rim *c* protects the edge of the mirror, and also by its prominence protects in some degree its surface from injury, and the said rim, where the obverse side that contains the business designation is in a separate piece from the body of the mirror, also unites and holds such separate piece to the back of the mirror.

I do not confine myself to any particular shape or size in my combined mirror and card; but by means of my invention I produce a combined portable article of use and convenience which can be easily carried in the pocket of a coat or dress.

Another feature of my invention consists in combining with the mirror or the card a pin-cushion or pin-holder formed in the rim *c*, which I perforate to receive pins *d*, as shown in the drawings, the perforations being more or less in number and confined to one side or made all around the rim, as may be preferred by the maker.

What I claim as new, and desire to secure by Letters Patent, is—

A new article of manufacture, the device herein described, the same consisting of the business-card *b* and the mirror *a*, which are retained together by the rim *c*, whose periphery is perforated, and the parts thereby form a combined business-card, mirror, and pin-cushion, substantially as specified.

In witness whereof I have signed my name hereto in presence of two witnesses.

HENRY H. BROWNE.

In presence of—

J. VAN SANTVOORD,
GUSTAV BERG.
